United States Patent

Des. 241,617
Patented Sept. 28, 1976

241,617

EXPANSIBLE ANCHOR BOLT

Illar Toomingas, Enskede, Sweden, assignor to Telefonaktiebolaget L. M. Ericsson, Stockholm, Sweden

Claims priority, application Sweden Mar. 19, 1975

Filed Sept. 2, 1975, Ser. No. 609,363

Term of patent 14 years

Int. Cl. D8—08

U.S. Cl. D8—272

FIG. 1 is a perspective view of an expansible anchor bolt showing my design, the other side of the bolt being similar to the illustrated one.

I claim:

The ornamental design for an expansible anchor bolt, as shown and described.
